UNITED STATES PATENT OFFICE.

CORA ETHEL KELLER, OF SPRINGFIELD, MISSOURI.

SUSPENDERS FOR CHILDREN'S CLOTHES.

Application filed October 24, 1921. Serial No. 509,827.

To all whom it may concern:

Be it known that I, CORA ETHEL KELLER, a citizen of the United States, residing at Springfield, in the county of Greene and State of Missouri, have invented certain new and useful Improvements in Suspenders for Children's Clothes; and I do declare the following to be a full, clear, and exact description of the invention, such as will enable others skilled in the art to which it appertains to make and use the same.

This invention relates broadly to improvements in garment supporters, and it has more particularly reference to a device of this class which is especially designed for suspending or supporting children's clothing.

The principal object of the invention is to generally improve upon clothes suspenders of this class by providing an arrangement which is simple, effective, durable and extremely comfortable, the same being so constructed that it equally distributes the weight of the clothing upon the shoulders, chest and back and in so doing assists in holding the body of the child erect at all times.

Another object of the invention is to provide a clothes suspending device of this class which embodies no metal, the same being composed of washable material which can be kept clean at all times.

Another object of the invention is to provide a suspender which is such in construction that provision is made for attachment of buttons at various points for supporting all kinds of clothing, the waist band having buttons thereon and serving to eliminate one or more ordinarily necessary waists, thus permitting less clothing to be worn.

A further object of the invention is to provide a suspender which merely includes a waist-encircling band, shoulder straps, and a single strip of material or a band which is stitched and connected with the shoulder strap and waist-encircling band and is folded and connected with the latter in such a way that it serves to equally distribute the weight of the garments on the shoulders and back as above suggested, provides loops to which hose supporters can be connected and provides a means for spreading of the shoulder straps, the entire device only necessitating two buttons which serve to permit it to be readily applied and removed. Of course, only two buttons are absolutely necessary, but under practically all circumstances, many

buttons will be provided for supporting a particular kind of clothing and the buttons will be arranged at various points for effective use by boys or girls.

Other objects and advantages of the invention will be apparent during the course of the following description.

In the accompanying drawings forming a part of this specification and in which like numerals are employed to designate like parts throughout the same:

Figures 1, 2 and 3 are respective rear, front and side views illustrating the improved garment supporter in position on a child.

Figure 4 is an enlarged detail rear perspective view of the supporter showing the construction and arrangement of the straps and parts more clearly.

Referring to the drawings by numerals, 1 designates a fabric band which is designed to encircle the child's waist. It is to be noted that this band is to be of such a size as to permit it to be loose so that it will allow a child perfect freedom of movement of the body. It is also to be noted that no elastic is embodied in the band. The ends of the latter are separated and these ends are buttoned or otherwise detachably connected together as indicated at 2. Stitched or otherwise permanently secured at their opposite end to this band, are a pair of straps 3 which may be conveniently termed shoulder straps, since they pass up over the front of the child, over the shoulders and down across the back and through the medium of another strap, to be hereinafter described, place the entire weight of the garments suspended by the device, on the shoulders and upper portion of the back and chest. In order to acquire an equal distribution of the weight of the garment on the parts of the body above mentioned, I prefer to make use of a single strip of material, one end of which

is buttoned or otherwise detachably connected at 11 with the intermediate portion of the right hand shoulder strap (see Fig. 4), and the portion 10^a of the strip being extended across and stitched or otherwise secured to the left-hand shoulder strap at the point shown. This part 10^a extends either across the wearer's back or chest according to the manner of arranging the suspenders on the body. The strip of material from the point 5 is extended downwardly and beyond the waist-encircling band and

is then extended upwardly again and stitched to said band at the point 6. By extending the strip of material in this manner, a loop 8 is provided which is well adapted for connection to a hose supporter. It may be conveniently mentioned here that a small piece of reinforcing material 9 may be stitched to the loop to give it strength. Proceeding with the aforesaid strip of material, it will be seen that it is extended upwardly from the point last mentioned and is stitched at the point 5^a to the left-hand shoulder strap. The strip is then extended across and connected with the other shoulder strap and is folded and stitched in a manner already described to form a second substantially V-shaped weight distributing strap-member and an additional loop for connection to the hose supporter on this side of the child. From the foregoing, it is obvious that the single strip of material provides portions 10 and 10^a to extend across either the back or the chest of the child according to the manner of wearing the suspenders and the V-shaped portions 4 of the strip of material provide weight-distributing strap members and loops for connection to the child's hose supporter.

It is yet to be pointed out that the complete suspender will be provided with a plurality of buttons 7 disposed at suitable points to permit the child's clothing to be attached to them. Also, a short diagonal reinforcing strap 12 will be disposed at the points indicated for the purpose of reinforcing the article.

By carefully considering the description in connection with the drawing, persons familiar with devices of this class will doubtless be able to obtain a clear understanding of the invention. Therefore, a more lengthy and detailed description is deemed unnecessary.

Since probably the best results may be obtained with the construction and arrangement herein shown and described, this is taken as the preferred embodiment of the invention. However, I wish it to be understood that minor changes coming within the scope of the subjoined claims may be resorted to if desired.

I claim:

1. A garment supporter of the class described comprising a waist-encircling band, shoulder straps connected to said band, and weight-distributing strap members connected to the shoulder straps at points adjacent the upper portions of the back and chest of the wearer, said strap-members being

connected to said band intermediate their ends at points substantially diametrically opposite one another.

2. The structure set forth in claim 1, the intermediate portions of the weight-distributing strap-members being extended beyond the waist-encircling band to provide loops for connection to hose supporters or the like.

3. A garment supporter of the class described comprising a waist encircling band having its ends detachably connected together, a pair of shoulder straps connected to said waist encircling band, V-shaped weight distributing strap-members connected to said shoulder straps at points adjacent the chest and upper portion of the back, being connected intermediate their ends to the waist encircling band at diametrically opposite points, said points of connection of the last named strap-members to the waist encircling band being between the points of connection of the shoulder straps with the latter, loops for connection of the hose-supporters or the like, and means connecting the shoulder straps together and extending cross-wise of the back and chest for preventing spreading of the shoulder straps.

4. A garment supporter of the class described comprising a waist-encircling band having its ends detachably connected together, a pair of shoulder straps connected at their opposite ends to said band at points where the band crosses the stomach and back of the wearer, and a single strip of material detachably connected at one of its ends to one of the shoulder straps adjacent the intermediate portion of the latter, said strip of material being extended across the chest of the wearer and connected with the other shoulder strap at a point corresponding to that first mentioned, the strip being then extended downwardly, beyond the waist band, upwardly and stitched to the latter to form a loop, the strip being then extended upwardly and stitched to the last named shoulder strap to form a substantially V-shaped weight distributing strap-member, the strip of material being finally extended across the back of the wearer and connected to the first named shoulder strap, and being again stitched to the last named shoulder strap and waist band in the aforesaid manner to provide a second V-shaped weight-distributing member and another loop.

In testimony whereof I have hereunto set my hand.

CORA ETHEL KELLER.
